ROTARY DUPLICATING APPARATUS**Wilhelm Ritterfeld, Berlin-Dahlem, and Gerhard Ritterfeld, Berlin-Grunewald, Germany****Application May 19, 1955, Serial No. 509,604
In Germany October 1, 1948****Public Law 619, August 23, 1954
Patent expires October 1, 1968****16 Claims. (Cl. 101—132.5)**

The present invention relates to a duplicating method and apparatus, and more particularly to a duplicating apparatus for printing spaced portions of a master sheet adjacent each other on a copy sheet.

It is one object of the present invention to duplicate spaced portions of a master sheet on to a copy sheet in such manner that the duplicated portions are printed adjacent each other on the copy sheet.

It is another object of the present invention to hold the copy sheet stationary while a duplicating roller moves the master sheet past a counter pressure roller which is in an inoperative position spaced from the duplicating roller.

It is a further object of the present invention to provide stripper means for separating the copy sheet from the master sheet so that the print cannot be smudged.

It is a still further object of the present invention to provide a shifting means for automatically shifting a pressure roller into engagement with the master sheet when a desired portion of the master sheet passes the printing line, and to shift the counter pressure roller away from the duplicating roller when an undesired portion of the master sheet passes the printing line, or when printing of the respective copy sheet is to be terminated.

It is yet an object of the present invention to provide means for shifting the counter pressure roller in such manner that on all copy sheets fed to the printing line a head portion of the master sheet is printed, while different selected line portions are printed on each copy sheet.

It is also an object of the present invention to provide means for shifting the counter pressure roller to its operative position when a selected line of the master sheet passes the printing line, and to provide automatic means to print in addition to the head portion a different selected line during each revolution of the duplicating roller.

It is another object of the present invention to automatically operate moistening means for moistening the copy sheet together with the pressure roller so that portions of the copy sheet which are to be printed are moistened.

With these objects in view, the present invention mainly consists in a method of duplicating from at least one master sheet at least two portions spaced from each other a first distance on to a copy sheet in a position spaced from each other a second smaller distance, comprising, in combination, the steps of moving the master sheet and the copy sheet in contact with each other in transporting direction through a duplicating station while the first portion of the master sheet passes through the duplicating station, separating the copy sheet from the master sheet while the master sheet moves relative to the duplicating station through the first distance, moving the copy sheet and the master sheet at the duplicating station again into contact with each other while the second portion of the master sheet passes through the duplicating

2

station whereby the first and second portions of the master sheet are duplicated on the copy sheet spaced a second distance smaller than the first distance.

An apparatus according to the present invention mainly comprises a driven duplicating roller, means on the duplicating roller for holding a master sheet, a pressure roller cooperating with the duplicating roller along a printing line, movable supporting means supporting the pressure roller for movement between an operative position cooperating with the duplicating roller and an inoperative position spaced from the duplicating roller, the rollers being adapted to grip a copy sheet at the printing line and transport the same in printing engagement with the master sheet only when the pressure roller is in the operative position, means for maintaining the copy sheet stationary when the pressure roller is in the inoperative position, and selectively operable shifting means connected to the duplicating roller and actuated by rotation thereof, the shifting means engaging the movable supporting means and moving the same and therewith the pressure roller automatically and positively during each revolution of the duplicating roller through a selective cycle of movement between the operative and inoperative positions so as to print selected spaced portions of the master sheet adjacent each other on the copy sheet.

Preferably, stripper means are provided for separating the copy sheets from said duplicating roller and from the master sheet after the copy sheets have passed through the printing line.

Movable moistening means are provided for moistening the copy sheets, and are shifted by the shifting means to an operative position for moistening the copy sheets in the area which is to be printed.

Preferably, a first cam unit is provided for operating the counter pressure roller for printing a head portion of the master sheet, and such first cam unit also operates the moistening means. A second cam unit is preferably provided for operating the counter pressure roller to print selected line portions of the master sheet. The relative position between the first cam unit and the second cam unit can be adjusted so that lines can be selected from the master sheet for being printed adjacent the head portion of the master sheet reproduced on the copy sheet.

The second cam unit is preferably automatically shifted after each revolution of the duplicating roller so that on consecutive copy sheets the same head portion, and consecutive line portions, are printed from the master sheet. Such automatic shifting means for the second cam unit can be disconnected so that the desired line is selected by manual operation.

The duplicating method according to the present invention is of particular advantage for work schedules in factories since it permits the printing of the head portion and a line portion referring to a particular operation on a single copy sheet, although only a single master sheet is used. It is, however, also possible to attach to the duplicating roller a master sheet having the head portion only and another master sheet comprising all line portions from which the respective lines are selected for printing on the copy sheet and for this purpose, two clamping means may be provided on the duplicating roller for holding the master sheets.

The novel features which are considered as characteristic for the invention are set forth in particular in the appended claims. The invention itself, however, both as to its construction and its method of operation, together with additional objects and advantages thereof, will be best understood from the following description of specific embodiments when read in connection with the accompanying drawings, in which:

Fig. 1 is a mirrorscript master sheet;

Fig. 1a is a copy sheet printed from the master sheet shown in Fig. 1 in accordance with the present invention;

Fig. 2 is an axial sectional view showing a cam unit for operating the counterpressure roller and the moistening device in a duplicating machine according to the present invention;

Fig. 3 is a side elevation illustrating the automatic shifting means for the cam unit;

Fig. 4 is a side elevation showing the operating means for controlling the printing roller and the moistening device;

Fig. 5 is a side elevation showing the operating means for shifting the pressure roller; and

Fig. 6 is a side elevation showing a side elevation of a stripper arrangement for spacing the copy sheet from the master sheet.

Referring now to the drawings, Fig. 1 is a schedule written in mirrorscript on a master sheet. The text comprises a head portion which is to be printed on all copy sheets, and a number of line portions. A special line may be arranged between the head portion and the line portion, and may be considered part of the head portion. According to the present invention the same head portion together with a single line selected from the line portion is printed on each copy sheet in such manner that the line portion for instance line 5 in Fig. 1a appears directly adjacent to the head portion on the copy sheet, although it is spaced from the head portion on the master sheet. In other words, lines intermediate the head portion and the selected line are omitted on the copy sheet.

Figs. 2, 3 and 4 illustrate a cam arrangement for operating the printing rollers and the moistening means and by which portions of the master sheet of varying width and a varying text portion can be printed adjacent the head portion.

According to the present invention, a cam unit including cams 68-77 are mounted on a cam shaft 79 which is operatively connected to the duplicating roller for rotation therewith. The cams 68-77 have effective projecting cam track portions of different lengths. The cam unit is movable in axial direction so that only the cam portion which corresponds to the width of the line which is to be moistened and printed, is effective, and acts on the cam follower levers 66 and 67. The cam units 68-77 can be turned and adjusted in circumferential direction for determining the moment of engagement between the cam follower levers 66 and 67 and the effective cam track portions whereby printing of a selected line spaced from the head portion is effected.

Transporting means are connected to this device for automatically shifting the cam unit 68-77 rearwardly for a distance corresponding to one line during each revolution of the cam shaft. Consequently, printing takes place during the next following revolution from the next following line of the master sheet corresponding to the automatic adjustment of the cam unit. The axial shifting of the cam unit is carried out by turning the threaded spindle 61 whereby the threaded nut 62 is moved on guide rod 62a.

Two cam discs 100 are fixedly secured to the cam shaft 79 and serve the purpose of printing and moistening the head portion of the master sheet. Two cam follower levers 101 and 102 cooperate with the cam discs 100, the cam follower lever 101 actuating the moistening means for printing the head portion, and the cam follower lever 102 actuating the counterpressure roller for printing the head portion.

During each operation the head portion is first printed. After the transport of the copy sheet, which will be described hereinafter, the selected line of the master sheet is moistened and printed.

In order to print a line which is spaced from the head portion by other lines, the hollow shaft 85 is turned together with the cam unit 68-77 through the gear 78

in rearward direction to such extent that the cam follower levers 66 and 67 are not actuated until the master sheet line to be printed is carried by the rotating duplicating roller to the printing line in which it is located opposite the counterpressure roller.

The automatic transport of the cam unit a selected distance in rearward direction is carried out in the following manner:

When the nut 62 is moved by operation of the spindle 61, the stepped member 63 is shifted so that the step thereon, corresponding to the distance which the cam unit is to be transported is placed in a position located opposite an actuating lever 64 and a releasing lever 65.

The cam shaft 79 turns one revolution, and the cam 89 associated with the stepped member 63 actuates the switching lever 81. The switching lever 81 can be arrested in an inoperative position so that the automatic transport is disconnected. When the switching lever 81 engages a recessed portion in the cam 89, the stepped member 63 is pivoted into a position located opposite the abutment edge 92 of the actuating lever 64 and the abutment edge 94 of the releasing lever 65. The locking pawl 82 which is urged by spring 83 into engagement with the ratchet wheel 84, turns the same together with the hollow shaft 85 and with the cam unit 68-77. A transporting pawl 88 is mounted turnable about pin 89 and is urged by a spring 87 into engagement with the transporting wheel 86. The actuating lever and the releasing lever 65 are urged by springs 90 and 93 against the stop pin 95 of the disc 91 which is rigidly secured to the cam shaft 79. The abutment edge 94 is arranged a small distance forwardly of the abutment edge 92. When the stepped member 63 is in operative position for effecting a desired transport, the abutment edge 94 engages the stepped member 63, and the releasing lever 65 is stopped.

The pin 96 of the locking pawl 82 moves onto the cam portion 97 of the releasing lever 65 and is shifted out of engagement with the ratchet wheel 84. The abutment edge 92 of the actuating lever 64 engages the same step as the releasing lever 65, but a little later than releasing lever 65 whereby the transporting pawl 88 is maintained in its position and stops the transporting wheel 86 together with the cam unit 68-77 while the spring 90 is tensioned which corresponds to the start of the transporting operation. Due to the fact that the hollow shaft 85 is at a standstill and that the cam shaft 79 turns, the spiral spring 98 is tensioned. Since the cam unit 68-77 is stopped, the cams are turned rearwardly through a distance corresponding to the width of the lines which was selected by adjusting the stepped member 63. Consequently, the cam follower levers 66 and 67 are actuated at a later moment during the next following revolution. The end of the recessed portion of the cam disc 89 effects return of the stepped member 63 through lever 81 whereby the abutment edges 92 and 94 are released which corresponds to the end of the transporting operation. The spring 93 effects forward movement of the releasing lever 65, and the spring 90 moves the actuating lever 64 and the releasing lever 65 into engagement with the stop pin 95. During this operation, the pin 96 has run off the cam portion 97, and the locking pawl 82 engages the ratchet wheel 84 and locks the same. During this operation, the hollow shaft 85 and the cam units 68-77 are pressed by the spiral spring 98 against pawl 99. Since pawl 99 rotates with the cam shaft 79, the cam unit 68-77 also rotates. The locking pawl 82 effects the turning of the follow shaft 85 together with the cam unit 68-77.

The spiral spring 98 has the additional purpose of returning the hollow shaft 85 together with the cam unit 68-77 step-by-step or continuously to initial position when the locking pawl 99 and the transporting pawl 88 are disengaged by suitable manually operated means.

Fig. 4 illustrates the mechanism for transferring the

motion of the cam follower levers 66 and 67 to the printing means and to the moistening device. The cam follower lever 66 pivots about a fixed pin 66a and pulls the link 66b in the direction of the arrow. The pin 66c of the link 66b moves in an elongated slot and tensions the spring 66e. Such tensioning overcomes the force exerted by a weaker spring 66f so that the spring 66e moves the pin 66g and the link 66d. The link 66d pivots the moistening lever 66h about the pin 66i, and the moistening means 66k move to an operative position engaging the copy sheet, or the supporting table, respectively. Due to this arrangement, the engagement of the moistening means 66k is resilient, and the amount of transferred moisture does not vary.

Since the moistening means 66k pivot about the pin 15 66i, the engagement face of the moistening felt pad moves along a circular arc. The face 66l is so positioned that it extends tangentially with respect to this circular arc. Consequently, the felt pad engages always the same spot even if worn off after prolonged use.

When the cam unit turns further, the cam follower lever 67 is operated by the same cam track portion and turns about the pin 67a to move the link 67b in the direction of the arrow so that the toggle lever means 67c and 67d are straightened. The pressure roller 67e 25 is thereby pivoted about the pin 67g in the direction of the arrow by the link 67f so that the pressure roller 67e is pressed against the duplicating roller 67h. The amount of pressure can be adjusted by turning the eccentric member 67k. Due to the action of the spring 67i, the cam follower lever 67 resiliently engages the cam.

Fig. 5 illustrates the control and shifting of the pressure roller. The pressure roller 110 is spaced from the duplicating roller 111 in initial position. When the duplicating roller 111 turns about the axis 112 in the direction of the arrow, the lug 113 of the disk 114 engages the roller 115. The lever 116 pivots about the pin 117 and moves the link 118 in the direction of the arrow whereby the toggle lever means 119 and 120 are straightened and the counterpressure roller 110 is pressed against the duplicating roller 111. The pin 121 engages during this operation the recess 122 in the locking lever 123. The locking lever 123 maintains the counterpressure roller 110 in its position until the lug 124 of the disk 114 engages the roller 125 whereby locking lever 123 is pivoted about pin 126 so that the recess 122 releases the pin 121. The spring 127 pulls the link 118 in a direction opposite to the direction of the arrow so that the toggle lever means 119 and 120 return to initial position whereby the counterpressure roller 110 is moved away from the duplicating roller 111. Due to the fact that the lug 124 can be mounted in different holes 128 of the disk 114, the width of the printed lines can be determined.

Fig. 6 illustrates a stripping mechanism which prevents sliding of the copy sheet on the turning duplicating roller when the counterpressure roller is spaced from the duplicating roller. The counterpressure roller is mounted on a lever 198, and a lever 199 is mounted in a slot of lever 199. The lever 199 carries the stripper bar 200 which extends along the entire duplicating roller. The lever 201 which pivots about the fixed pin 202 is moved by the link 203 when the supporting lever 198 is shifted whereby the stripper bar 200 is placed in the desired position. The resiliently mounted pin 204 presses the copy sheet 205 under the stripper bar 200 when assuming during the printing operation the position illustrated in dash and dot lines in Fig. 6. Fig. 6 also shows a first master sheet 59, first clamping means 59a for holding the master sheet 59 on the duplicating roller, a second master sheet 159 for a head portion of the text superimposed on master sheet 159, and held by second clamping means 159a.

It will be understood that each of the elements described above, or two or more together, may also find a useful application in other types of rotary duplicators differing from the types described above.

While the invention has been illustrated and described as embodied in a duplicator for printing spaced portions of a master sheet on a copy sheet adjacent each other, it is not intended to be limited to the details shown, since various modifications and structural changes may be made without departing in any way from the spirit of the present invention.

Without further analysis, the foregoing will so fully reveal the gist of the present invention that others can by applying current knowledge readily adapt it for various applications without omitting features that, from the standpoint of prior art, fairly constitute essential characteristics of the generic or specific aspects of this invention and, therefore, such adaptations should and are intended to be comprehended within the meaning and range of equivalence of the following claims.

What is claimed as new and desired to be secured by Letters Patent is:

1. A rotary duplicator comprising, in combination, a driven rotary duplicating roller; means on said duplicating roller for holding a master sheet having a head portion and a plurality of line portions; a pressure roller cooperating with said duplicating roller along a printing line; movable supporting means supporting said pressure roller for movement between an operative position cooperating with said duplicating roller and an inoperative position spaced from said duplicating roller, said rollers being adapted to grip a copy sheet at said printing line and transport the same in printing engagement with said master sheet only when said pressure roller is in said operative position; means for maintaining the copy sheet stationary when said pressure roller is in said inoperative position; stripper means located in the bight between said rollers for separating copy sheets after printing from said duplicating roller and from the master sheet; linking means connecting said stripper means with said movable supporting means for movement with the same; moistening means for moistening copy sheets fed to said rollers; a movable support for said moistening means supporting the same for movement between an operative moistening position and an inoperative position; and selectively operable shifting means connected to said duplicating roller and actuated by rotation thereof, said shifting means including first means engaging said movable supporting means and second means engaging said movable support and moving the same and therewith said pressure roller and said moistening means automatically and positively at least twice during each revolution of said duplicating roller through a selective cycle of movements between said operative and inoperative positions so as to print the head portion and selected spaced line portions of said master sheet adjacent each other on the copy sheet.

2. A rotary duplicator comprising, in combination, a driven rotary duplicating roller; means on said duplicating roller for holding a master sheet; a pressure roller cooperating with said duplicating roller along a printing line; movable supporting means supporting said pressure roller for movement between an operative position cooperating with said duplicating roller and an inoperative position spaced from said duplicating roller, said rollers being adapted to grip a copy sheet at said printing line and transport the same in printing engagement with said master sheet only when said pressure roller is in said operative position; means for maintaining the copy sheet stationary when said pressure roller is in said inoperative position; moistening means for moistening copy sheets fed to said rollers movable to a moistening position engaging a copy and being in said moistening position spaced a predetermined distance from said printing line; a movable support for said moistening means; and first and second cam means connected to said duplicating roller for rotation therewith, said first cam means engaging said movable supporting means for moving said

pressure roller during each revolution of said duplicating roller at least twice to said operative position and back to said inoperative position for printing a head portion and a selected line portion from said master sheet on the copy sheet, said first cam means having cam portions of equal length to produce equally spaced imprints on the copy sheet, said second cam means engaging said movable support for moving said moistening means at least twice to said moistening position and into engagement with said copy sheet for moistening the same before passing through said printing line, said second cam means being associated with said first cam means for moving said moistening means to said moistening position when said first cam means move said movable supporting means to a position corresponding to said inoperative position of said pressure roller.

3. A rotary duplicator comprising, in combination, a driven rotary duplicating roller; means on said duplicating roller for holding a master sheet; a pressure roller cooperating with said duplicating roller along a printing line; movable supporting means supporting said pressure roller for movement between an operative position cooperating with said duplicating roller and an inoperative position spaced from said duplicating roller, said rollers being adapted to grip a copy sheet at said printing line and transport the same in printing engagement with said master sheet only when said pressure roller is in said operative position; means for maintaining the copy sheet stationary when said pressure roller is in said inoperative position; moistening means for moistening copy sheets fed to said rollers; a movable support for said moistening means; first and second cam means connected to said duplicating roller for rotation therewith, said first cam means engaging said movable supporting means for moving said pressure roller during each revolution of said duplicating roller at least twice to said operative position for printing a head portion and a selected line portion from said master sheet on the copy sheet, said second cam means engaging said movable support for moving said moistening means into engagement with said copy sheet for moistening the same before passing through said printing line; and means for adjusting the relative position of said first and second cam means.

4. A rotary duplicator comprising, in combination, a driven rotary duplicating roller; means on said duplicating roller for holding a master sheet; a pressure roller cooperating with said duplicating roller along a printing line; movable supporting means supporting said pressure roller for movement between an operative position spaced from said duplicating roller, said rollers being adapted to grip a copy sheet at said printing line and transport the same in printing engagement with said master sheet only when said pressure roller is in said operative position; means for maintaining the copy sheet stationary when said pressure roller is in said inoperative position; moistening means for moistening copy sheets fed to said rollers movable between an operative and an inoperative position; a movable support for said moistening means; a first cam unit engaging said movable supporting means and said movable support for moving said pressure roller and said moistening means to operative positions for printing a head portion of said master sheet and for moistening the copy sheet; and a second cam unit engaging said movable supporting means and moving the same to said operative position for printing a line portion from said master sheet; and means for adjusting the relative position between said first cam unit and said second cam unit.

5. A rotary duplicator as claimed in claim 4 and including locking means for locking said movable supporting means in said inoperative position of said pressure roller; and wherein said first cam unit include cam track portions for unlocking said movable supporting means

so as to permit movement of said pressure roller to said operative position.

6. A rotary duplicator comprising; in combination, a driven rotary duplicating roller; means on said duplicating roller for holding a master sheet; a pressure roller cooperating with said duplicating roller along a printing line; movable supporting means supporting said pressure roller for movement between an operative position cooperating with said duplicating roller and an inoperative position spaced from said duplicating roller, said rollers being adapted to grip a copy sheet at said printing line and transport the same in printing engagement with said master sheet only when said pressure roller is in said operative position; means for maintaining the copy sheet stationary when said pressure roller is in said inoperative position; moistening means for moistening copy sheets fed to said rollers movable between an operative and an inoperative position; a movable support for said moistening means; a first cam unit engaging said movable supporting means and said movable support for moving said pressure roller and said moistening means to operative positions for printing a head portion of said master sheet and for moistening the copy sheet; a second cam unit engaging said movable supporting means and moving the same to said operative position for printing a line portion from said master sheet; and means for adjusting the relative position between said first cam unit and said second cam unit; and means for automatically turning said second cam unit after each revolution of said duplicating roller for printing consecutive line portions from said master sheet on consecutively fed copy sheets adjacent a head portion printed on all copy sheets.

7. A rotary duplicator comprising, in combination, a driven rotary duplicating roller; means on said duplicating roller for holding a master sheet; a pressure roller cooperating with said duplicating roller along a printing line; movable supporting means supporting said pressure roller for movement between an operative position spaced from said duplicating roller, said rollers being adapted to grip a copy sheet at said printing line and transport the same in printing engagement with said master sheet only when said pressure roller is in said operative position; means for maintaining the copy sheet stationary when said pressure roller is in said inoperative position; moistening means for moistening copy sheets fed to said rollers movable between an operative and an inoperative position; a movable support for said moistening means; a first cam unit engaging said movable supporting means and said movable support for moving said pressure roller and said moistening means to operative positions for printing a head portion of said master sheet and for moistening the copy sheet; and a second cam unit engaging said movable supporting means and moving the same to said operative position for printing a line portion from said master sheet, said first and second cam unit being turnable relative to each other for selecting different line portions from said master sheet; and manually adjustable means for turning said first and second cam units relative to each other for selecting line portions of said master sheet for printing together with the head portion of the master sheet.

8. A rotary duplicator comprising, in combination, a driven rotary duplicating roller; means on said duplicating roller for holding a master sheet; a pressure roller cooperating with said duplicating roller along a printing line; movable supporting means supporting said pressure roller for movement between an operative position cooperating with said duplicating roller and an inoperative position spaced from said duplicating roller, said rollers being adapted to grip a copy sheet at said printing line and transport the same in printing engagement with said master sheet only when said pressure roller is in said operative position; means for maintaining the copy sheet stationary when said pressure roller is in said inoperative position.

erative position; moistening means for moistening copy sheets fed to said rollers movable between an operative and an inoperative position; a movable support for said moistening means; stripper means located in the bight between said rollers for separating copy sheets from said duplicating roller and from the master sheet after printing; a first cam unit engaging said movable supporting means and said movable support for moving said pressure roller and said moistening means to operative positions for printing a head portion of said master sheet and for moistening the copy sheet; a second cam unit engaging said movable supporting means and moving the same to said operative position for printing a line portion from said master sheet, said first and second cam unit being turnable relative to each other for selecting different line portions from said master sheet; and manually adjustable means for turning said first and second cam units relative to each other for selecting line portions of said master sheet for printing together with the head portion of the master sheet.

9. A rotary duplicator comprising, in combination, a driven rotary duplicating roller; means on said duplicating roller for holding a master sheet; a pressure roller cooperating with said duplicating roller along a printing line; movable supporting means supporting said pressure roller for movement between an operative position cooperating with said duplicating roller and an inoperative position spaced from said duplicating roller, said rollers being adapted to grip a copy sheet at said printing line and transport the same in printing engagement with said master sheet only when said pressure roller is in said operative position; means for maintaining the copy sheet stationary when said pressure roller is in said inoperative position; moistening means for moistening copy sheets fed to said rollers movable between an operative and an inoperative position; a movable support for said moistening means; stripper means located in the bight between said rollers for separating copy sheets from said duplicating roller and from the master sheet after printing; linking means connecting said stripper means with said movable supporting means for movement with the same; a first cam unit engaging said movable supporting means and said movable support for moving said pressure roller and said moistening means to operative positions for printing a head portion of said master sheet and for moistening the copy sheet; a second cam unit engaging said movable supporting means and moving the same to said operative position for printing a line portion from said master sheet, said first and second cam unit being turnable relative to each other for selecting different line portions from said master sheet; and manually adjustable means for turning said first and second cam units relative to each other for selecting line portions of said master sheet for printing together with the head portion of the master sheet.

10. In a rotary printing device comprising, in combination, a rotary printing roller adapted to support a printing form having a text thereon having lines extending in axial direction of said printing roller, said printing roller being adapted to move the printing form through a printing line; a pressure roller cooperating with said printing roller at said printing line; movable supporting means supporting said pressure roller for movement between an operative position engaging said printing roller and an inoperative position spaced from said printing roller, said rollers being adapted to grip a supplied copy sheet along said printing line and to transport the same in printing engagement with said printing roller only when said pressure roller is in said operative position; holding means for holding the copy sheet stationary when said pressure roller is in said inoperative position; a plurality of cam follower means connected to said movable supporting means; a shaft connected to said printing roller for rotation therewith; a rotary cam device including a plurality of cam means and being mounted on

5 said shaft, each of said cam means including a plurality of cam discs having cam tracks corresponding to portions of said text, each of said cam means being shiftable in axial direction between a plurality of positions in which a different number of said cam discs cooperate with the associated cam follower roller, at least one of said cam means being turnable on said shaft for adjusting the position of said cam tracks with respect to said cam follower means; and a ratchet device for turning said at least one cam means on said shaft.

15 11. An arrangement as set forth in claim 10 and including automatic operating means actuated in response to turning of said printing roller for turning one of said cam means relative to said supporting means after each revolution of said printing roller.

12. In a rotary printing device comprising, in combination, a rotary printing roller adapted to support a printing form having a text thereon having lines extending in axial direction of said printing roller, said printing roller being adapted to move the printing form through a printing line; a pressure roller cooperating with said printing roller at said printing line; movable supporting means supporting said pressure roller for movement between an operative position engaging said printing roller and an inoperative position spaced from said printing roller, said rollers being adapted to grip a supplied copy sheet along said printing line and to transport the same in printing engagement with said printing roller only when said pressure roller is in said operative position; holding means for holding the copy sheet stationary when said pressure roller is in said inoperative position; a plurality of cam follower means connected to said movable supporting means; a shaft connected to said printing roller for rotation therewith; a rotary cam device including a plurality of cam means and being mounted on said shaft, each of said cam means including a plurality of cam discs having cam tracks corresponding to portions of said text, each of said cam means being shiftable in axial direction between a plurality of positions in which a different number of said cam discs cooperate with the associated cam follower roller, at least one of said cam means being turnable on said shaft for adjusting the position of said cam tracks with respect to said cam follower means; a ratchet device for turning said at least one cam means on said shaft; and an automatic operating means actuated by said printing roller for actuating said ratchet device after each revolution of said printing roller.

13. A rotary duplicator comprising, in combination, a driven duplicating roller adapted to support at least one master sheet and to move the same through a printing line; a pressure roller cooperating with said duplicating roller at said printing line; movable supporting means supporting said pressure roller for movement between an operative position engaging said duplicating roller along said printing line and an inoperative position spaced from said duplicating roller; supply means for supplying sheets to said rollers so that said rollers grip a supplied copy sheet along said printing line and transport the same in printing engagement with said master sheet only when said pressure roller is in said operative position; holding means for maintaining the copy sheet stationary when said pressure roller is in said inoperative position thereof; cam means rotating with said duplicating roller and engaging said holding means for moving the same into a position releasing said copy sheet when said pressure roller is in said operative position; separating guide means located adjacent said duplicating roller in the region of the printing line and adapted to project between said duplicating roller and a copy sheet maintained stationary by said holding means; and selectively operable shifting means connected to said duplicating roller and actuated by rotation thereof, said shifting means engaging said movable supporting means and moving the same and therewith said pressure roller auto-

matically and positively during each revolution of said duplicating roller through a selected cycle of movements from said operative position to said inoperative position and back to said operative position in such manner that when undesired portions of said master sheet are moved by said duplicating roller through said printing line, said pressure roller is in its operative position, and so that when desired portions of said master sheet are moved by said duplicating roller through said printing line, said pressure roller is in its operative position for printing said desired portion of the master sheet on the copy sheet immediately following the last preceding printed desired portion.

14. A rotary duplicator comprising, in combination, a driven duplicating roller adapted to support at least one master sheet and to move the same through a printing line; a pressure roller cooperating with said duplicating roller at said printing line; movable supporting means supporting said pressure roller for movement between an operative position engaging said duplicating roller along said printing line and an inoperative position spaced from said duplicating roller; supply means for supplying sheets to said rollers so that said rollers grip a supplied copy sheet along said printing line and transport the same in printing engagement with said master sheet only when said pressure roller is in said operative position; means for maintaining the copy sheet stationary when said pressure roller is in said inoperative position thereof; rotary cam means driven from said duplicating roller so as to turn in timed relationship with the master sheet, said cam means engaging said movable supporting means and moving the same and therewith said pressure roller automatically and positively during each revolution of said duplicating roller through a selected cycle of movements from said operative position to said inoperative position when undesired portions of said master sheet are moved by said duplicating roller past said printing line, and again to said operative position for printing desired portions of the master sheet on the copy sheet adjacent to matter previously printed by said master sheet; a moistening device for moistening said copy sheet and being movable between a moistening position and a retracted position; and operating means including cam means driven from said duplicating roller and connected to said moistening device to move the same into said moistening position when said one roller is in said inoperative position.

15. A rotary duplicator as claimed in claim 14 wherein said rotary cam means which engage said movable supporting means have cam portions of equal length so that said rollers move said copy sheet for a predetermined distance each time said one roller is in said operative

position and so that the spacing of imprints on said copy sheet is equal; and wherein said moistening device is spaced in said moistening position a corresponding predetermined distance from said printing line so as to be located intermediate imprints on said copy sheet when said one roller is in said inoperative position.

16. A rotary duplicator comprising, in combination, a driven duplicating roller; first clamping means on said duplicating roller extending parallel to the axis thereof and adapted to clamp a first master sheet along an edge extending normal to the lines thereon; a second clamping means on said duplicating roller adapted to clamp a second master sheet superimposed upon a portion of said first master sheet so that said duplicating roller moves said master sheet through a printing line; a pressure roller cooperating with said duplicating roller at said printing line; movable supporting means supporting said pressure roller for movement between an operative position engaging said duplicating roller along said printing line and an inoperative position spaced from said duplicating roller; supply means for supplying sheets to said rollers so that said rollers grip a supplied copy sheet along said printing line and transport the same in printing engagement with said master sheets only when said pressure roller is in said operative position; means for maintaining the copy sheet stationary when said pressure roller is in said inoperative position thereof; and rotary cam means driven from said duplicating roller so as to turn in timed relationship with the master sheets, said cam means engaging said movable supporting means and moving the same and therewith said pressure roller automatically and positively during each revolution of said duplicating roller through a selected cycle of movements from said operative position to said inoperative position when undesired portions of said master sheets are moved by said duplicating roller past said printing line, and again to said operative position for printing desired portions of the master sheets on the copy sheet adjacent to matter previously printed by said master sheets.
